CLAIM

The ornamental design for a plant stand, as shown and described.

DESCRIPTION

FIG. 1 is a perspective view of a plant stand, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a bottom view of the plant stand shown with environmental subject matter.

The portions of the plant stand shown in broken line form no part of the claimed design. The broken line showing of plants in FIG. 8 is for the purpose of illustrating environmental subject matter and forms no part of the claimed design.

1 Claim, 8 Drawing Sheets(56)
